UNITED STATES PATENT OFFICE

150,882

DESIGN FOR A SEWING MACHINE FRAME

Michael McCann, Union, N. J., assignor to The
Singer Manufacturing Company, Elizabeth,
N. J., a corporation of New Jersey

Application October 2, 1946, Serial No. 133,688

Term of patent 14 years

(Cl. D70—1)

To all whom it may concern:

Be it known that I, Michael McCann, a citizen of the United States, residing at Union, in the county of Union and State of New Jersey, have invented a new, original, and ornamental Design for a Sewing Machine Frame, of which the following is a specification, reference being had to the accompanying drawing, forming a part thereof.

Fig. 1 is a front perspective view of a sewing machine frame showing my new design.

Fig. 2 is a rear perspective view of the sewing machine frame shown in Fig. 1.

I claim:

The ornamental design for a sewing machine frame, as shown.

MICHAEL McCANN.
